UNITED STATES PATENT OFFICE.

ARTHUR A. WOODWARD, OF DETROIT, MICHIGAN, ASSIGNOR TO SKINNER AUTOMOTIVE DEVICE CO., INC., OF DETROIT, MICHIGAN, A CORPORATION OF CALIFORNIA.

SLEEVE-PRINCIPLE ENGINE LUBRICATION.

Application filed December 16, 1926. Serial No. 155,243.

This invention pertains to novel and advantageous means associated with or forming part of the lubrication system of an internal-combustion engine, especially one of the movable or reciprocatory sleeve type, whereby to withdraw or remove surplus lubricating oil from the sliding piston and from the sleeve or sleeves during their movements, and, if desired, to purify such abstracted oil and return it to the engine for further use.

One aim of the invention is to provide simple means for intermittently withdrawing the surplus oil, probably more or less contaminated, from the piston, and removing the excess oil from the sleeve or sleeves practically continuously, and, preferably, through a single port through the cylinder-wall desirably below, or in the zone of suction action of, the engine intake port.

For the attainment of these and other objects the system or structure has been devised which has been illustrated in detail in the accompanying drawings forming a part of this specification, and throughout the several views of which like reference numerals have been employed to designate the same parts of the structure.

Although this construction represents a present desirable and preferred embodiment of the invention, those skilled in this art will readily understand that it may be incorporated in different physical forms all constructed along the lines of the fundamental principles involved.

In these drawings—

Fig. 1 is a central, vertical, fragmentary, cross-section through one cylinder of a multi-cylinder, internal-combustion engine or motor equipped with the new structural and functional features;

Fig. 2 is a fragmentary section through the same engine-cylinder at right angles to that of Fig. 1;

Fig. 3 is a partial plan of the engine;

Fig. 4 is a fragmentary elevation of the inner sleeve;

Fig. 5 is a similar view of the outer sleeve;

Fig. 6 is a partial elevation of the inner surface of the engine-cylinder; and

Fig. 7 is an enlarged, horizontal section on line 7—7 of Fig. 1.

Referring to the plurality of views of these drawings, it will be noted that the water-jacketed engine-cylinder has been character-

ized 11, its inlet and outlet ports 12 and 13, respectively, the engine crank-case 14, the crank-shaft 15, the connecting-rod 16, the piston 17, the inner sleeve 18, the outer sleeve 19, the intake-manifold 21, and the exhaust-manifold 22.

The sleeves are reciprocated in the usual way by eccentrics, and the cylinder, sleeves and piston are lubricated in any approved fashion, as by a splash system or by a forced-feed structure.

The piston is of the form and style set forth in United States Patent No. 1,502,922, and is fitted with a plurality of piston-rings 23 in corresponding grooves of the piston, the lowermost of such grooves, back of its piston-ring, being connected at 24 with a channel 25 on the outer surface of the piston and disposed lengthwise thereof in alignment with a port 26 through the engine cylinder-wall below the fuel admission-port 12. Diametrically opposite such longitudinal channel, such lower, piston-ring groove has a small bleeder-port or air-inlet 27 connected thereto and extended inwardly through the piston-wall, whereby the groove at this point is in direct connection with the hollow interior of the piston, which, of course, is in open communication with the inside of the crank-case.

Thus air drawn into the groove through such small admission-port will come from the inside of the piston and from the crank-case, tending to keep the latter at a slight vacuum to prevent the outward leakage of oil through the shaft-bearings.

The inner sleeve 18, in alignment with the piston-channel 25 and the cylinder-port 26, has a lengthwise channel 28 on its outer surface terminating at its lower end in a port or hole 29 through the sleeve, which intermittently registers or connects with the piston-channel, although the latter during the ascent of the piston passes upwardly beyond and uncovers such port.

Two vertically-spaced ports 31 and 32 extend through the outer sleeve in alignment with the cylinder-port 26 and the inner sleeve channel or groove 28, the arrangement and location of these ports being such that the cylinder-port 26 will be closed by the outer sleeve during the period the piston uncovers or opens port 29, and will be in communication with the lower piston-ring groove through the piston-channel 25, the inner

sleeve-port 29, and the inner sleeve-channel 28, through the one or the other outer sleeve-port 31 or 32, during a substantial portion of the travel of the piston.

5 The outer surface of the inner sleeve has a plurality of horizontal oil-grooves 33 extended all the way around the sleeve and connecting with a lengthwise channel 34 on the outer face of the sleeve, but angularly offset or out of alignment with the channel 28 on the same sleeve, and such inner sleeve has other, lower, horizontal oil-grooves 35 which extend almost, but not quite, all the way around the sleeve, their ends 36 and 37 being spaced apart on opposite sides of the channel 28, with which they do not, therefore, communicate.

10 A longer, longitudinal channel 38 is provided on the external surface of the outer sleeve, out of alignment with the ports 31 and 32, such channel having a port 39 extended inwardly through the sleeve and in communication with the channel 34 of the inner sleeve, channel 38, during the reciprocation of the outer sleeve, being in constant or uninterrupted connection or overlapping relation with a horizontal groove 41 cut in the inner surface of the engine-cylinder and joined to the cylinder-port 26.

15 20 25 30 One or more horizontal, circumferential oil-grooves 42 on the external face of the outer sleeve extend completely around the latter and intersect the lengthwise channel 38, whereas other, similar, lower oil-grooves 43 on the same surface of the same sleeve are shorter and do not connect with such channel nor with the ports 31 and 32.

20 25 30 35 From the above description and the illustration, it will be apparent that the two nested or telescoping, sliding sleeves have oil-grooves on their surfaces in constant or uninterrupted communication with the engine cylinder-port 26, in contrast to the intermittent connection of the piston-ring, oil-collecting groove with the same port.

30 35 40 45 A somewhat-flattened, tubular manifold 44 extends along the outsides of the several engine-cylinders and is connected to all of their cylinder-ports 26, and such manifold, in turn, by means of a pipe 45, is joined to the interior of an oil rectifier or purifier 46 of known construction, such oil-reclaiming appliance having a jacket 47 surrounding it, so that its contents may be heated by means of the exhaust gases of the manifold 22 to which the jacket is operatively connected.

40 45 50 55 Such rectifier is joined by a pipe 48 to the intake-manifold of the engine, whereby the prevailing, sub-atmospheric pressure therein creates a suction in the rectifier, the piping specified and the various grooves and channels connected continuously or at intervals with the cylinder-port 26.

60 65 In addition, the oil purifier has an oil-discharge pipe 49 associated with an oil-

70 75 80 85 90 95 100 105 110 115 120 125 130 pump 51 inside of the engine crank-case, and by means of which the reclaimed or purified oil is returned under atmospheric pressure to the crank-case or other part of the lubrication system of the engine, without interrupting or disturbing the existing, sub-atmospheric conditions in the rectifier under the action of which the contaminated oil is purified.

The system operates substantially as follows:

During the reciprocatory movements of the piston, the lower piston-ring scrapes or wipes off the excess oil from the interior, cylindrical surface of the inner sleeve and causes it to be delivered into the piston-ring groove back of the piston-ring, whereby the oil arrives in such groove after it has had ample opportunity to perform its lubricating function.

The suction always present in the rectifier and at each cylinder-port 26, is intermittently applied to such corresponding piston-groove through the ports 31 and 32, channel 28, port 29 and channel 25, and its contents, which consist of the above-specified oil and any fuel in liquid or gaseous form, products of combustion, vapors, etc., tending to escape down past the piston into the crank-case and the oil-supply therein, and aerating air entering the piston bleeder-port 27, are withdrawn interruptedly as aerated, contaminated or impure oil, delivered into and reclaimed in the rectifier under sub-atmospheric pressure, and under heat if required, and returned as pure oil to the engine for further use, the oil, vapors and gasifiable constituents of the polluted oil being drawn into the engine intake-manifold and cylinders, where they are burned, with resulting operating economy.

The air entering through the small admission-port of the piston-groove breaks the existing vacuum, thus facilitating the withdrawal of the contents of such groove, as well as preliminarily aerating them for more efficient reclamation in the rectifier.

In this way, the excess oil is prevented from reaching the combustion chamber, where it would be uselessly burned with resultant harmful effects, and the main oil-supply in the crank-case is precluded from becoming contaminated or fouled.

While all of this is taking place, the oil in the grooves of the two sleeves connected with their lengthwise channels 34 and 38 is withdrawn continuously through port 39, channel 41 and port 26, and delivered in like manner into the rectifier, being mixed as it passes along conduits 44 and 45 with the oil from the pistons, it being understood that it is such mixture which is refined in the rectifier and returned to the engine.

In view of the fact that the cylinder-port 26 is longitudinally directly below the engine

- and sleeve intake-ports, the constant removal of the excess oil from the sleeves at this point assures that it will not come under the influence of the suction existing at such 5 ports and be drawn therethrough, with resultant wasteful combustion in the cylinders and the production of an objectionable, smoky exhaust.
- The invention, as defined by the appended 10 claims is susceptible of satisfactory embodiments in several commercial forms, and is, therefore, not limited to the particular one hereinabove set forth in detail.
- I claim:
- 15 1. In an internal-combustion engine, the combination of an engine-cylinder having inlet and exhaust ports, movable sleeve-means in said cylinder controlling said ports, a reciprocatory piston in said sleeve-means, 20 means to lubricate said piston, sleeve-means and cylinder, means to remove fluids from around said piston intermittently, and means to remove fluids from around said sleeve-means continuously during the operation of 25 the engine.
2. In an internal-combustion engine, the combination of an engine-cylinder having inlet and exhaust ports, movable sleeve-means in said cylinder controlling said ports, 30 a reciprocatory piston in said sleeve-means, means to lubricate said cylinder, sleeve-means and piston, means to remove fluids from around said piston intermittently through a cylinder-port, and means to re- 35 move fluids from around said sleeve-means continuously during the operation of the engine through the same port.
3. In an internal-combustion engine, the combination of an engine-cylinder having 40 inlet and exhaust ports, movable sleeve-means in said cylinder controlling said ports, a reciprocatory piston in said sleeve-means, means to lubricate said cylinder, sleeve-means and piston, means to remove fluids from around said piston intermittently, and 45 means to remove fluids from around said sleeve-means continuously during the operation of the engine at a point in substantial longitudinal register with said cylinder inlet-port.
- 50 4. In an internal-combustion engine, the combination of an engine-cylinder having inlet and exhaust ports, movable sleeve-means in said cylinder controlling said ports, a reciprocatory piston in said sleeve-means, 55 means to lubricate said cylinder, sleeve-means and piston, means to remove fluids from around said piston intermittently through a cylinder-port in substantial longitudinal alignment with said cylinder inlet-port, and means to remove fluids from 60 around said sleeve-means continuously during the operation of the engine through the same cylinder-port.
- 65 5. In an internal-combustion engine, the combination of an engine-cylinder having inlet and exhaust ports, movable inner and outer sleeves in said cylinder controlling said ports, a reciprocatory piston in said inner sleeve, means to lubricate said cylinder, 70 sleeves and piston, means to withdraw fluids from around said piston intermittently during its operation, and means to withdraw fluids from between said sleeves continuously during the operation of the engine.
6. In an internal-combustion engine, the combination of an engine-cylinder having inlet and exhaust ports, movable inner and outer sleeves in said cylinder controlling said ports, a reciprocatory piston in said inner sleeve, means to lubricate said cylinder, 75 sleeves and piston, means to withdraw fluids from around said piston intermittently during its operation, and means to withdraw fluids from between said outer sleeve and 80 said cylinder continuously during the operation of the engine.
7. In an internal-combustion engine, the combination of an engine-cylinder having inlet and exhaust ports, movable inner and outer sleeves in said cylinder controlling said ports, a reciprocatory piston in said inner sleeve, means to lubricate said cylinder, 85 sleeves and piston, means to withdraw fluids from around said piston intermittently during its operation, and means to withdraw fluids from between said outer sleeve and 90 said cylinder and from between said sleeves continuously during the operation of the engine.
8. In an internal-combustion engine, the combination of an engine-cylinder having inlet, exhaust and oil ports, movable inner and outer sleeves in said cylinder controlling said inlet and exhaust ports, a reciprocatory 95 piston in said inner sleeve, means to lubricate said cylinder, sleeves and piston, means to withdraw fluids from around said piston intermittently during its operation through said cylinder oil-port, and means to withdraw fluids continuously during the operation of the engine through said cylinder oil-port from between said outer sleeve and said cylinder and from between said sleeves.
9. In an internal-combustion engine, the combination of an engine-cylinder having inlet and exhaust ports and an oil-port below and in substantial longitudinal register with said inlet-port, movable inner and outer sleeves in said cylinder controlling said inlet 105 and exhaust ports, a reciprocatory piston in said inner sleeve, means to lubricate said cylinder, sleeves and piston, means to withdraw fluids from around said piston intermittently during its operation through said cylinder oil-port, and means to withdraw fluids continuously during the operation of the engine from between said outer sleeve and said cylinder and from between said sleeves through said cylinder oil-port.

10. In an internal-combustion engine, the combination of an engine-cylinder having inlet and exhaust ports, transversely-channeled movable sleeve-means in said cylinder, a-transversely-channeled piston reciprocatory in said sleeve-means, means to lubricate said cylinder, sleeve-means and piston, means to withdraw the contents of said piston-channel intermittently during the operation of the piston, and means to withdraw the contents of said sleeve-means channel continuously during the operation of the engine. 45
11. In an internal-combustion engine, the combination of an engine-cylinder having inlet and exhaust ports, movable inner and outer sleeves in said cylinder controlling said ports, one of said sleeves having an oil-groove on its surface bearing on the other sleeve, means to lubricate said cylinder, sleeves and piston, means to withdraw fluids from around said piston intermittently during its operation, and means to withdraw fluids from said sleeve-groove continuously during the operation of the engine. 50
12. An internal-combustion engine-cylinder having fuel-inlet and exhaust ports, an oil-port therethrough below and in substantial longitudinal alignment with said inlet-port, and a transverse groove on its inner surface connecting with said oil-port and extending part way only around the cylinder. 55
13. In an internal-combustion engine, the combination of an engine-cylinder having fuel-inlet and exhaust ports and an oil-port below said inlet-port, movable inner and outer sleeves in said cylinder controlling said inlet and exhaust ports, a transversely externally grooved piston reciprocatory in said inner sleeve and having an air inlet-port communicating with said piston-groove at a point angularly remote from said cylinder oil-port and a longitudinal channel in alignment with said cylinder-port and connected to said transverse groove, means to lubricate said cylinder, sleeves and piston, 60 said inner sleeve having an external longitudinal channel in alignment with said cylinder oil-port and having a port through the sleeve adapted to connect the longitudinal channels of said sleeve and piston, said outer sleeve having spaced ports in alignment with and adapted to come into register with said cylinder oil-port, said inner sleeve having an external transverse oil-groove connecting with the second external longitudinal channel angularly offset with respect to said cylinder oil-port, said outer sleeve having an external transverse oil-groove connecting with an external longitudinal channel in alignment with and having a port connecting with said inner sleeve second channel, 65 said cylinder on its inner wall having a transverse groove connecting with said cylinder oil-port and with said outer-sleeve longitudinal channel, an oil-rectifier, a conduit connecting said rectifier to said cylinder oil-port, a conduit connecting said rectifier to the intake-manifold of the engine, whereby to subject said rectifier and cylinder oil-port to suction, and means to return the rectified lubricant to the lubrication system of the engine, whereby the contents of said piston-groove are withdrawn intermittently in aerated condition and the contents of said sleeve-grooves are withdrawn continuously 70 during the operation of the engine, both contents being rectified and returned to the engine for re-use, the air, vapors and gases in the rectifier passing to the engine intake-manifold for combustion in the engine. 75
- In witness whereof I have hereunto set my hand.
- ARTHUR A. WOODWARD.
